(57) **CLAIM**

The ornamental design for a canning jar tool, as shown and described.

DESCRIPTION

FIG. 1 is a top right perspective view of a canning jar tool;
FIG. 2 is a top plan view thereof;
FIG. 3 is a left side view thereof;
FIG. 4 is a bottom plan view thereof;
FIG. 5 is a right side view thereof;
FIG. 6 is a front elevation view thereof; and,
FIG. 7 is a rear elevation view thereof.

The broken lines depict portions of the canning jar tool, which form no part of the claimed design.
